(57) **CLAIM**

The ornamental design for a garden hose, as shown and
described.

DESCRIPTION

FIG. 1 is a perspective view of a garden hose showing our
new design;

FIG. 2 is a side elevational view thereof;

FIG. 3 is an elevation view of the opposite side thereof;

FIG. 4 is a top plan view thereof, the bottom plan view being
a mirror image thereof; and,

FIG. 5 is an end view thereof.

The broken line portions in FIG. 1 through FIG. 5 show
unclaimed features of the garden hose and form no part of
the claimed design.

The garden hose is shown with a symbolic break at one end.
The appearance of any portion of the garden hose beyond the
symbolic break line forms no part of the claimed design.
